IRRIGATING SYRINGE

Aldean W. Whitton, Jr., Glenview, Ill., assignor to American Hospital Supply Corporation, Evanston, Ill., a corporation of Illinois

Filed Aug. 14, 1962, Ser. No. 71,279

Term of patent 14 years

(Cl. D83—12)

FIG. 1 is a perspective view of an irrigating syringe embodying my new design;

FIG. 2 is a side elevational view of the syringe;

FIG. 3 is a top view; and

FIG. 4 is a bottom view.

I claim:

The ornamental design for an irrigating syringe, as shown.
